(57) **CLAIM**

The ornamental design for a dancing cactus plush toy, as shown and described.

DESCRIPTION

FIG. 1 is a front, right and top perspective view of a dancing cactus plush toy, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings and the ghosting areas within the broken lines show portions of the dancing cactus plush toy that form no part of the claimed design.

1 Claim, 7 Drawing Sheets
